UNITED STATES PATENT OFFICE

MAURICE GOUDARD, OF NEUILLY SUR SEINE, FRANCE

CARBURETOR

Application filed November 4, 1925, Serial No. 66,808, and in Belgium December 17, 1924.

This invention relates to carburetors having a plurality of spraying nozzles controlled by a throttle valve.

This invention is an improvement on the invention disclosed in my copending application for "carburetors", S. N. 754,622, filed December 8, 1924.

With known carburetors comprising a principal nozzle and a slow speed nozzle delivering at all speeds of the engine, it is found that the carburation is satisfactory at starting and when running full speed, but when the valve is turned into position very close to that in which it is completely shut, a "poor" mixture is produced.

The insufficient output in almost closed position produces the so called "gap" in carburation at the slow speed limit and is due to the fact that the strong suction which is exerted on the slow speed nozzle in the position where the valve is almost closed diminishes too rapidly when the latter moves into the position corresponding to a slightly larger opening.

With certain constructions, the slow speed nozzle contributes an excessive amount for fast running. This is particularly the case when the edge of the valve covering the auxiliary full inlet opens in the upstream direction. In such constructions, the terminal orifice of the conduit of the slow speed nozzle in the conduit of the principal nozzle is always in the zone of suction created by the movement of the valve into slightly open position. The slow speed nozzle therefore contributes too much mixture at part way open positions of the valve.

The present invention has for its object to remedy the poverty or insufficiency of output at the end of the slow speed period and to remedy its excess towards the end of the full speed period.

In order that the invention may be clearly understood, it will now be described with reference to the accompanying drawings, but it is to be observed that the description and drawings are given merely by way of example.

Figs. 1 and 2 show, in vertical section, a portion of two carburetors having a full

speed nozzle and a slow speed nozzle, the carburetors being constructed according to the invention.

As regards all the parts of the carburetor other than the obturating valve or throttle, these are constructed and arranged in the manner shown in my copending application S. N. 754,622 above referred to, including for instance a constant level chamber *c*, provided with a float *c'*.

d is the body or principal conduit of the carburetor, in which is located the principal nozzle *a*.

e is the slow speed conduit opening into the body *d* by means of a horizontal passage.

An auxiliary nozzle *b* is located in the axis and at the bottom of the slow speed conduit *e*.

As regards the obturating or throttling device, this is so arranged that in the closed position a peripheral portion thereof covers or masks the opening of the slow speed conduit *e*. With this end in view the device is preferably formed as a butterfly valve *f* turning about an axis perpendicular to the axis of the carburetor, and, in the case of the carburetor shown at Fig. 1, located substantially in a plane perpendicular to the axis of the body of the carburetor passing through the edge of the orifice of the slow speed conduit towards the nozzle.

The butterfly valve is provided on the side directed towards the slow speed conduit with an enlarged or thickened portion *f'* adapted in the closed position of the valve to cover or mask the said conduit *e*.

According to the principle of the invention the want of an adequate delivery from the passages, when passing from slow speed towards high speed, is remedied by providing the arrangements shown at Figs. 1 and 2.

In the embodiment shown at Fig. 1 the forward edge, that is the edge towards the nozzle, of the opening of the slow speed conduit *e* is located substantially in the transverse plane passing through the axis of the valve *f*. The valve is provided with the enlarged portion *f'* which in this case is formed spherical in the neighborhood of the slow speed orifice where coming into contact with the wall of the principal conduit. From this spheri-

cal surface extend a series of passages opening on the suction side of the valve. These passages increase progressively in diameter, in such a way that as the valve is opening passages of progressively greater diameter come opposite the slow speed orifice while the enlarged portion of the valve is still covering such orifice and is moving upwardly with the flow of carbureted air.

10 The result of this arrangement is that a progressively increasing suction is brought to bear upon the slow speed nozzle, since air is being drawn through passages *i*, *m* and *n* of progressively increasing section.

15 Referring to Fig. 2, where the opening of the slow speed conduit may be slightly downstreamward of a plane perpendicular to the axis of the main conduit and passing through the axis of the valve, the valve *f* is provided 20 with an enlarged portion *h* covering the slow speed orifice in the closed position of the valve. The edge of this enlarged portion towards the nozzle may, when the valve is in closed position, lie downstreamward of, or 25 in, a plane perpendicular to the axis of the main conduit and passing through the valve axis. In the said enlarged portion *h*, a single passage *i'* is provided so arranged that in the closed position of the valve, the passage opens 30 at one end on the suction surface of the valve, and at the other end slightly upstreamward of the terminal orifice of the slow speed passage. The upstream edge of the enlargement *h* produces, in the slightly open position, a strong suction on the slow speed conduit and as the passage *i'* approaches the 35 terminal orifice of the slow speed passage a gradually increasing output section or delivery passage is provided. Increasing suction on the slow speed nozzle is obtained 40 through the combination of the single passage in the valve with means for gradually increasing the radial flow of air over the surface of the opening of the conduit *e*, during 45 the time that the upstream edge of the enlargement *h* maintains a strong suction at the level of the opening of the slow speed conduit *e*.

50 It will be observed that both as regards the constructions illustrated at Fig. 1 and Fig. 2, the enlarged portion of the valve opens in the direction of movement of the air, the result being that in both cases in the open positions of the valve the suctions upon the principal nozzle and upon the slow speed nozzle are substantially equal. Under these conditions, an excessive output is not to be feared at high speeds from the slow speed nozzle.

55 As will be clearly understood and as appears moreover from what has already been stated, the invention is not limited in any way to the methods of application or the constructional embodiments more particularly 60 described, but all modifications are included

falling within a fair interpretation of the claims.

What I claim and desire to secure by Letters Patent of the United States of America is:—

70 1. A carburetor comprising in combination a main nozzle, an auxiliary nozzle, a main mixture conduit, an auxiliary mixture conduit having a terminal orifice in said main conduit, and a valve positioned in the main conduit so as to obstruct said terminal orifice when in closed position, said valve being operable to gradually uncover said terminal orifice while simultaneously opening 75 passage through the main conduit, said valve further having a plurality of passages of different section therethrough for coaction with the terminal orifice.

80 2. A carburetor comprising in combination a main nozzle, an auxiliary nozzle, a main mixture conduit, an auxiliary mixture conduit having a terminal orifice in said main conduit, and a rotatable valve positioned in the main conduit so as to obstruct said terminal orifice when in closed position, said valve being operable to gradually uncover said terminal orifice while simultaneously opening 85 passage through the main conduit, said valve further having a plurality of passages therethrough of different sections, said passages 90 being positioned so as to align successively with the terminal orifice during the opening movement of the valve in the order of their increasing sections.

95 In testimony whereof I have hereunto set 100 my hand.

MAURICE GOUDARD.
